UNITED STATES PATENT OFFICE

153,794

DESIGN FOR A THERAPEUTIC CABINET

George H. Hansen, Mission, Kans., Gerhard J. Schroer, Kansas City, Mo., and Conrad J. Curtis, Overland Park, Kans., assignors to C. Earl Hovey, Kansas City, Mo., trustee

Application March 1, 1948, Serial No. 144,844

Term of patent 14 years

(Cl. D83—1)

To all whom it may concern:

Be it known that we, George H. Hansen, Gerhard J. Schroer and Conrad J. Curtis, a citizen of the United States residing at 5903 Buena Vista Street, Mission, Kansas; a citizen of the United States residing at 4238 Agnes Avenue, Kansas City, Missouri, and a citizen of the United States residing at 8203 Spruce Street, Overland Park, Kansas, have invented a new, original, and ornamental Design for a Therapeutic Cabinet, of which the following is a specification, reference being had to the accompanying drawing, forming a part thereof.

Fig. 1 is a perspective view of a therapeutic cabinet in a closed position, showing our new design.

Fig. 2 is a perspective view of the cabinet in an open position.

Fig. 3 is a top plan view of the cabinet as shown in Fig. 1, and

Fig. 4 is a side elevational view thereof.

We claim:

The ornamental design for a therapeutic cabinet, as shown.

GEORGE H. HANSEN.
GERHARD J. SCHROER.
CONRAD J. CURTIS.
